UNITED STATES PATENT OFFICE.

MINOR F. H. GOUVERNEUR AND FAIRFAX H. GOUVERNEUR, OF BALTIMORE, MARYLAND, ASSIGNORS TO LOCKE INSULATOR CORPORATION, OF BALTIMORE, MARYLAND, A CORPORATION OF MARYLAND.

CHAIN LINK FOR INSULATORS.

Application filed March 8, 1922. Serial No. 541,967.

The invention relates to insulators used in the transmission of electric power currents, and more particularly to devices for mechanically connecting insulators of the so-called strain type in series, or to the support or to the conductor.

The principal object of our invention is to simplify the form of connector now used for the purposes stated above by eliminating all extraneous parts and by making the connector simply to connect and disconnect without the use of tools, but rendering accidental disconnection of the parts of the connector impossible when the same is in use. To this end the principal feature of our invention, generally considered, is to provide a link comprising a pair of counterpart members, either member preferably being adapted to extend through a passage in the insulator, each part of the connector having integral members thereon whereby the said parts may be interlockingly connected to form a rigid link.

Another feature of the invention is to provide a link for use in connection with insulators, the said link being composed of a pair of counterpart members of subsequent U-form, each member being provided with a socket portion and a lug portion, the lug portions being adapted to enter and engage within the socket portions of the opposite member.

Still another feature of our invention is to provide a link composed of a pair of substantially U-shaped counterpart members, the members each being furnished with a slotted socket portion the slots being so shaped as to permit of the parts being connected or disconnected only when the same are relieved of strain.

There are other features of the invention as will be apparent from the detailed description of the single embodiment of the device which has been illustrated in the accompanying drawings.

Figure 1 is a transverse vertical sectional view through an insulator of the Hewlett type showing our improved form of connector in side elevation as associated with the said insulator.

Figure 2 is a view, partially in side elevation and partially in section, showing the position of the connector parts in the act

of assembly or disassembly, the insulator being illustrated by dot and dash lines. 65

Figure 3 is a view similar to Fig. 1, showing the parts of the connector in interlocking engagement.

Figure 4 is a view in side elevation of the socket end of one of the connector members. 60

Figure 5 is a sectional view taken in the line 5—5 of Fig. 1, looking in the direction indicated by the arrows adjacent the ends of said section line.

Figure 6 is a perspective view of the clip 65 or locking mechanism which may be used to prevent the disassembly of the parts of the connector.

The numeral 1 designates an insulator of the strain type conforming in outline to the well known Hewlett form. These insulators are provided with a plurality of interlinking passages 2 and 3 by which, through the medium of a connecting device, they are either suspended in series or to supports or connected to the conductor. Although we have illustrated our connector as associated with the Hewlett type of insulator, it is to be understood that we do not limit our invention to this type, since it is obvious that it may be used with many of the varied forms of strain insulators now so commonly employed. 70 75

The connector or link 4 preferably comprises a pair of counterpart members 5 each 80 of which is substantially U-shaped in outline. The arm 6 of each member is enlarged or increased in diameter and is provided with a hollow socket portion 7 terminated adjacent the end of each arm by an undercut 80 or inclined shoulder 8. Each socket portion is pierced by a slot 9 which may be provided with a T-head portion 10, as clearly shown in Fig. 4, the purpose of which will be pointed out hereinafter. It will be observed that 85 the head 10 of the slot 9 in each arm 6 is spaced from the shoulder 8 so as to provide intermediate the head 10 and the shoulder 8 a semi-cylindrical surface with a restricted opening. Intermediate the shoulder 8 and 90 the end of the arm 6 there is provided a curved bearing 11, the object of which will also hereinafter be described. The socket portion 7 extends on opposite sides of the head 10 of the slot 9 and communication is 95 had between the portion intermediate the

100 105

head 10 and the lower extremity of the socket 7 by means of an opening 12.

On the opposite end each member 5 is provided with a shank portion 13 terminating 5 adjacent the end in a lug portion 14 the lug 14 overhanging the stem 13 through an arc of substantially 180 degrees. The shoulders 15 formed by the overhanging portion of the lug 14 are preferably inclined at an 10 angle to the horizontal, as is clearly shown in Fig. 3.

The intermediate portion of each member 5 between the lug 14 and the socket portion 6 is preferably curved substantially in the 15 arc of a circle and is adapted to conform to the opening 2 or 3 within the insulator.

To connect the parts of the link the lug portions 14 are brought opposite to and in line with the portions 10 of the slots 9. The 20 parts are then moved transversely relatively to each other so as to enter the lug portions 14 within the socket portions 7, the slots 9 permitting the stems 13 to enter the recesses or socket portions. The parts 5 are then 25 moved in opposite directions so as to bring the shoulders 15 into engagement with the shoulders 8 and at the same time the stems 13 into engagement with the portions 11 at the outer ends of the socket portions to form 30 a bearing for the said stem, whereupon the parts will be interlockingly connected against further longitudinal movement and will be connected against lateral separation due to the face of the lug 14 engaging the 35 inner face or walls 16 of the socket portion. If desired a U-shaped spring clip 17 may then be forced over the lower lip 18 at the bottom of the slot, the lower arms of the spring engaging within the recess 12, the 40 upper portion of the clip so restricting the opening 10 as to prevent any possibility of the adjacent lug 14 withdrawing from the said opening. It will be obvious that but a single clip is required since the parts of 45 the link are rigid and it will therefore be impossible for the lug 14 and the member 5 upon which the clip is placed to withdraw from the slot 10 of its interconnected member until the lug 14 of the interconnected member is in turn withdrawn from 50 the socket of the first named member.

The device as here shown and described is formed of but two parts and is substantially symmetrical in appearance when initially interlocked and provides curved or rounded surfaces on the exterior thereof towards the exterior face of the insulator. By this construction we avoid all corona points, since coronas will not form on curved or rounded 55 surfaces.

By extending the recesses 7 below the lips 18 we render it impossible, or practically impossible, for the parts of the link to be accidentally disengaged in service even when 60 the clip 17 is not employed, because if

the link is relieved of strain and a lifting force is applied the parts will move vertically and the tendency will be for the lugs to pass below the lips 18. That is, a vertical movement alone of the parts will not disconnect the same, since to disconnect the parts it is necessary to move them vertically relative to each other until the lugs 14 of both members are opposite the openings 10 and then move the members transversely in opposite directions. These movements, first in one direction and then at right angles to that direction, are obviously impossible when the parts are in service.

When used with the Hewlett type of insulator there is an additional safeguard against accidental disengagement inasmuch as the projecting lug or boss on the outer faces of the Hewlett insulator renders it impossible to either connect or disconnect 85 the parts until the same are inclined to the vertical axis of the insulator into substantially the position shown in Fig. 2.

The intermediate portions of the connector conform in contour to the shape of the 90 passage through the insulator, and the lug portions 14 are of such size as to permit the ready entry and withdrawal of the same to and from the insulator passage.

We claim:

1. A two-part link member for insulator chains comprising a pair of counterpart members of substantially U-shape with one arm longer than the other, the shorter arm terminating in a head and the longer arm 100 having its end portion enlarged and formed with a recess and a slot in its inner side and end communicating with the recess, the end of the slot most remote from the end being laterally widened, said slot and widened portion thereof being adapted to allow said shorter arm and head of the other member to pass therethrough to seat said head within said recess.

2. A two-part link member for insulator 110 chains comprising a pair of counterpart members of substantially U-shape with one arm longer than the other, the shorter arm terminating in a head and the longer arm having its end portion enlarged and formed 115 with a recess and a slot in its inner side and end communicating with the recess, the end of the slot most remote from the end being laterally widened, said slot and widened portion thereof being adapted to allow said shorter arm and head of the other member to pass therethrough to seat said head within 120 said recess, the enlarged portion of the longer arm being gradually curved and merging into the major portion.

3. A two-part link member for insulator chains comprising a pair of counterpart members of substantially U-shape with one arm longer than the other, the shorter arm terminating in a head and the longer arm 130

having its end portion enlarged and formed with a recess and a slot in its inner side and end communicating with the recess, the end of the slot most remote from the end being laterally widened, said slot and widened portion thereof being adapted to allow said shorter arm and head of the other member to pass therethrough to seat said head within said recess, said head defining a shoulder extending obliquely with respect to the axis of the insulator chain, and the wall of the recess engaged by said shoulder being correspondingly oblique.

4. A two-part link member for insulator chains comprising a pair of counterpart members of substantially U-shape with one arm longer than the other, the shorter arm terminating in a head and the longer arm having its end portion enlarged and formed with a recess and a slot in its inner side and end communicating with the recess, the end of the slot most remote from the end being laterally widened, said slot and widened portion thereof being adapted to allow said shorter arm and head of the other member to pass therethrough to seat said head within said recess, and a retaining member engageable with the inner wall of said enlarged portion at the edge of the widened portion of the slot therein for partially obstructing said widened portion.

5. A two-part link member for insulator chains comprising a pair of counterpart members of substantially U-shape with one

arm longer than the other, the shorter arm 35 terminating in a head and the longer arm having its end portion enlarged and formed with a recess and a slot in its inner side and end communicating with the recess, the end of the slot most remote from the end being 40 laterally widened, said slot and widened portion thereof being adapted to allow said shorter arm and head of the other member to pass therethrough to seat said head within said recess, the inner wall of the enlarged 45 portion having an opening spaced from the widened end of the slot, and a spring clip engaged upon said wall with its ends accommodated within said opening, the clip projecting into the widened portion of the 50 slot to obstruct passage of the head therethrough subsequent to assembly.

6. A two-part link member for insulator chains comprising a pair of counterpart members of substantially U-shape, one arm 55 of each terminating in a head and the other having its end portion enlarged and formed with a recess and a slot in its inner side and end communicating with the recess, the end of the slot most remote from the end being 60 laterally widened and adapted to allow the first mentioned arm and head of the other member to pass therethrough to seat said head within said recess.

In testimony whereof we affix our signatures.

MINOR F. H. GOUVERNEUR.
FAIRFAX H. GOUVERNEUR.
